Albert Schumacher

UNITED STATES PATENT OFFICE.

EMIL EBINGHAUS AND ALBERT SCHUMACHER, OF GEVELSBERG, GERMANY.

ROLLING-MILL.

No. 873,997.

Specification of Letters Patent.

Patented Dec. 17, 1907.

Application filed February 12, 1906. Serial No. 300,664.

To all whom it may concern:

Be it known that we, EMIL EBINGHAUS and ALBERT SCHUMACHER, citizens of the German Empire, residing at Gevelsberg, in the Province of Westphalia and Kingdom of Prussia, Germany, have invented certain new and useful Improvements in Rolling-Mills, of which the following is a specification.

10 This invention relates to improvements in rolling mills for making small articles in great numbers, such as railing heads, studs, keys and the like; it consists in the combination of a continuously revolving roller with a movable slide which moves to and fro in regular order and which forms the counter mold for the revolving roller. This slide is carried forward one way by a segment of toothed gearing engaging during a certain 20 period of its rotation with the corresponding teeth of a rack connected to the table or made in one piece with the same and it is pulled back, when it has become disengaged from the roller by means of a counterweight 25 suitably arranged so as to exert a pulling force in the proper direction upon the slide, as will be more fully described hereafter.

On the accompanying drawing the new rolling mill is shown in a vertical sectional view in Figure 1 in position where the segmental gearing and the rack of the slide are in gear with each other, in Fig. 2 that position of the slide plate is shown and of the roller, where the rack and toothed segment 35 are disengaged with each other and where the slide has been pulled back into its original position.

The machine is supported on a table 1, carrying in suitable guide ways the slide 2; 40 at one end of the slide is fixed a rope or chain 3 passing over a pulley 4 of a bracket 5 and to the end of which is suspended a counterweight 6 having the tendency to pull the slide always towards one side, the left in the 45 example shown, until it bears against the lateral projection 7 of the table 1. Right and left to both sides of the slide the table carries the forked standards, or uprights 8 which serve as guides for the brasses 9, indicated in 50 dotted lines, in which the shaft 10^a of the roller 10 is journaled; at one end the shaft carries a driving pulley 10^b by which the roller 10 is set in continuous rotation. It is 55 self evident that instead of this direct driving motion by a pulley and belt the roller

might be driven by suitable intermediate gear wheels; this only depends from the speed and from the power required or from the size of the articles to be made.

The roller 10 is provided with an exchangeable molding piece or caliber 11 fitted thereto firmly but taking only part of the circumference, say about one fifth or one sixth of the same, and in accordance herewith the roller is provided with a toothed segmental 60 part 12; this may be connected to the roller or fixed separately on the roller shaft. The slide 2 is in a similar and corresponding manner provided with an exchangeable molding piece 13 and with a rack 14 corresponding 65 with the toothed segment 12. The roller is pressed down by its own weight.

From the description given and from the drawing the working of the machine will now be easily understood to be as follows: A 70 piece of iron or steel, preferably made red hot is placed on the molding piece 13 and when the toothed segment 12 comes round and engages with the rack 14 the slide 2 is driven towards the right together with the 75 working piece upon it and this is pressed between the two molds 11 and 13 and thus receives its shape; as soon as the last tooth of the segment leaves the rack 14, the slide is pulled back by the rope and counterweight 80 3, 6, the worked piece or pieces can now be taken off and a new work piece be placed on the mold 13, when the same play is repeated. The brasses 9 are free to rise in or between 85 the standards 8, which have their slot or intervening guide-way open at the top. In consequence the roller 10 will readily yield upward in case of sudden jar, preventing 90 any injury. Also the insertion of thicker material to be operated on will be facilitated. 95

Having now described our invention and its mode of working, we declare that what we desire to be secured by Letters Patent is:

1. In rolling mill mechanism a longitudinally movable part and a die carried thereby, 100 in combination with an axially movable part, a co-operating die carried by the latter, and a frame adapted to support said parts and permit and guide such movements, the axially movable part being free to move vertically 105 upward for admitting greater thickness of material or preventing injury by sudden jars substantially as set forth.

2. In rolling mill mechanism a pair of co-operating die-carrying members, one moving 110

axially, the other longitudinally, means for operating one of said members and means whereby this member causes the operation of the other member, the axially moving member and its die being free to rise in case of sudden jar or to provide for the admission of thicker material substantially as set forth.

In testimony whereof we have affixed our signatures in presence of two witnesses.

EMIL EBINGHAUS.

ALBERT SCHUMACHER.

Witnesses:

OTTO KÖNIG,

OTTO CARNAP.
